UNITED STATES PATENT OFFICE.

HENRY BRUNT, OF BALTIMORE, MARYLAND.

DESIGN FOR A COVERED DISH.

SPECIFICATION forming part of Design No. 22,817, dated October 3, 1893.

Application filed September 6, 1893. Serial No. 484,945. Term of patent 3½ years.

To all whom it may concern:

Be it known that I, HENRY BRUNT, a citizen of the United States, residing at Baltimore, Maryland, have invented and produced 5 a new and original Design for a Covered Dish, of which the following is a specification, reference being had to the accompanying drawings, forming a part hereof.

Referring to the said drawings, Figure 1 is 10 a perspective view of the covered dish, and Fig. 2 a top view of the dish without the cover. Fig. 3 is a top view of the cover.

I describe the dish proper, as follows: The 15 general form of the body A as seen from its top is elliptical. The base which is beaded at its edge is of a similar shape. As seen from the side, the body flares out in a curved line between the points, a and b. Above the point b is a fillet c. The handles B of the 20 body are branched, and placed on the longer diametrical line; and they begin about the midway point d and flare outward in a curved

line. They are suitably decorated the design being in relief. At the junction of each branch of the handles, and the body, is a foliated design in relief which appears to be a continuation of the said branch and prevents an abrupt union of the two parts. The cover C as seen from the upper or the lower side, is of an elliptical form, but the ends are scalloped, and the upper surface has curved depressed loops extending one from each scallop to a point which is covered by a figure in relief. The handle D extends between these figures and is of foliated design with a decorated medallion at the crown. 25 30 35

I claim as my invention—

The design for a covered dish as herein shown and described.

HENRY BRUNT.
